UNITED STATES PATENT OFFICE.

THOMAS SPENCER MILLER, OF SOUTH ORANGE, NEW JERSEY.

METHOD AND APPARATUS FOR FUELING SHIPS AT SEA.

Application filed December 12, 1922. Serial No. 606,488.

My invention relates to supplying ships with oil and it has particular reference to the fueling of ships while travelling at considerable speed at sea.

5 Other and further objects of the invention will be apparent hereinafter and the novelty of the invention will be particularly pointed out in the appended claims.

My invention is illustrated in the accompanying drawings, in which Figures 1 and 2 are respectively a plan and elevation of the stern of a fueling ship connected to the bow of a ship to be fueled with the necessary lines in place; Fig. 3 is a view of the stern portion 15 of the fueling ship on a larger scale than that of Figs. 1 and 2; Fig. 4 is an elevational view of the stern portion of the fueling ship showing modified means for handling the various lines; Fig. 5 is an elevation of a hose jack 20 or a support for the fuel hose; Fig. 6 is a vertical section taken on line 6—6 of Fig. 5; Fig. 7 is a vertical section on the line 7—7 of Figure 5; Fig. 8 is a side elevation of the hook portion of a hanger designed to support 25 the hose; Fig. 9 is a rear view of the device shown in Fig. 8; Fig. 10 is a perspective view of the hanger shown in Figs. 8 and 9 with an oil hose in place; Fig. 11 is a plan view of a modified form of hose support; Fig. 12 is a 30 view in elevation of the hose support shown in Fig. 11; Fig. 13 is a view, partly in section, looking from the left of Fig. 12 showing a portion of the saddle or support proper cut away; Fig. 14 is a view in perspective showing the means for securing together at the 35 hose couplings of the jackstay sections, of securing the latter to the fuel hose, and Fig. 15 is a plan view of the arrangement shown in Fig. 14.

40 Referring to Figs. 1, 2 and 3, it will be seen that I have provided two elevated hawsers 2 and 3 connecting the rear portion of the fuel ship A with the bow of the ship B to be fueled. From each of the hawsers 2 and 45 3 I suspend a hose 30 for conducting the liquid fuel. A fixed line 1 known as a "distance hawser" usually very slack limits the distance between the ships although is not intended to act at a tow line. The hawsers 2 and 50 3 are attached to the fuel ship in a manner to permit the towing of the ship to be fueled as will be fully explained hereinafter. In Figs. 1 and 2 I have illustrated two hose and two supporting hawsers and in Fig. 4 an arrangement wherein but one hose is used but it will be understood that the number of

hose and hawsers used may be varied as desired, similar apparatus being used in connection with each hose and its supporting hawser.

60 The method of fueling by the apparatus illustrated in Figs. 1, 2 and 3 is carried out in the following manner:

(1) Both ships maneuver until the one to be fueled follows astern and in line with the fuel ship at the same speed at a suitable distance, for example about 450 feet or less. 65 (2) The fuel ship lowers a float to which are attached three manila lines, which are picked up by the ship to be fueled. By means 70 of these three lines, three hawsers are pulled over to the ship to be fueled. These lines comprise a hawser 1, to be referred to as a distance hawser, the function of which will be hereinafter described, and two towing and 75 supporting hawsers 2 and 3 from each of which a fuel hose is to be suspended. At the time the supporting hawsers 2 and 3 are pulled over, two messenger lines may conveniently be brought over. The function of these is to 80 pull over the fuel hose suspended from the hawsers in the manner to be described. The manner of conveying the lines above mentioned to the ship B forms no part of the present invention and the above procedure is 85 given as one of a variety of ways in which this may be accomplished.

86 The function of the distance hawser is to prevent the ships from exceeding a predetermined distance between them of, say 300 or 90 400 feet. The distance hawser is maintained slack, sagging considerably into the sea, and is not used for towing. The distance hawser has an additional function in that it tends automatically to maintain a uniform distance 95 between the ships for the reason that whenever there is a tendency for the towed ship to lose speed, the distance hawser will tighten, the sag will decrease and its tension will increase. This increased hawser tension effects 100 a partial slowing-down of the fuel ship and a gradual speeding-up of the towed ship and whenever the ships approach one another the distance hawser slackens, reduces its pull and the towed ship automatically settles back 105 to normal distance.

(3) The tension of the supporting hawsers is regulated by means of automatic tensioning engines 10 on the fueling ship and to which the hawsers are attached. It is desirable 110 that an approximately uniform tension be maintained in the supporting hawsers by

means of which the ship to be fueled is also towed. I prefer to use for this purpose automatic tension engines of the type invented by me and disclosed in my Patent No. 1,405,612 and the patents and applications therein referred to. The supporting hawsers 2 and 3 having each been put under tension by the automatic tension engines 10, 10, the fuel ship may increase her speed up to, say, nine or ten knots. During this period the ship to be fueled must regulate her revolutions so that the distance hawser will remain very slack.

I provide blocks 20, 20, through which the hawsers 2 and 3 pass respectively and to each of which is connected a line 25, operated by winch 390. Thus, by means of winches 390, 390, I may haul hawsers 2 and 3 down close to the deck, whereby each hose 30 may be attached, in a manner to be described.

(4) The speed of both ships having been regulated as indicated in the foregoing, the supporting hawsers 2 and 3 are hauled down close to the deck by operating winches 390, 390, in the manner described, so that they will be easily accessible to the men for hooking on the hose. This hauling down does not materially increase the tension in the hawsers 2 and 3, as the tension engines 10 pay out the requisite amounts of the hawsers.

(5) The oil hose 30 are now hooked on to their supporting hawsers by attaching the supporting hangers 31, spaced, say, every five feet. The problem of supporting a long flexible conduit, such as an oil hose, is rather complex. The tensile strength of the hose is not sufficient to bear the force necessary to support the hose when loaded. Furthermore, it is advisable to place considerable tension on the hose otherwise it will sag between transverse supports to such an extent that oil will not readily flow therethrough. Furthermore, if all the tension is applied at the ends, the weight of the hose when loaded would be sufficient to break it.

I have devised means for supporting the hose which consists in attaching a cable to the hose at regular intervals and making the length of cable between points of attachment 50 slightly shorter than corresponding sections of the hose, so that a predetermined tension is applied to the hose. The tension on the hose is limited by the cable so that there is no danger of severing the hose due to abnormal pull, when the ships pitch. By this means the tension in the hose can be distributed throughout its length and limited to a predetermined amount.

A section 32 of a cable or jackstay 35 is attached to each hose section by means of manila lashings, prior to hooking the hose on to the supporting hawsers by means of hangers 31, as shown in Figs. 14 and 15. The manner of accomplishing this is as follows:

(6) The jackstay sections 32 are conveniently

provided at the ends thereof with eye splices 131 and thimbles 132. A shackle 133 is passed through one thimble 132 and is secured to the end of the adjacent jackstay section by means of a pin 134 passing through shackle 133 and thimble 132 of that jackstay section, as is clearly shown in Fig. 15. The jackstay sections 32 may then be securely lashed to the hose 30 by means of lashing 135 which is passed over and under shackle 133 and 75 around the hose coupling 136, as shown. The hose 30 may be supported at coupling 136 by a strap 33, in which case, additional lashing of jackstay sections to the hose will be secured. It will be noted that when the hanger 31 is attached to the hose by means of the manila strap 33, as shown in detail in Figure 10, the strap 33 passes around both the oil hose and the jackstay section 32, whereby the latter is firmly bound to the hose. The 85 jackstay sections are preferably made approximately the length of the hose sections, it being preferred that the jackstay sections be about one inch shorter than the hose sections when the latter measure twenty feet. The jackstay sections are coupled, as shown in Fig. 15. The hose are then hauled to the ship to be fueled by means of the hauling or messenger lines previously brought over and are operated by the men on that ship. These 95 hauling lines are attached to plugs (not shown) provided at the end of each hose, which also prevent the entrance of water into the hose.

(6) After the hose, together with jackstays 35 have been completely drawn over and attached to the vessel to be fueled, the end of the last section of each jackstay is attached to the hook 48 of the support or hose jack denoted generally by 40. These supports 40 serve the dual function of supporting the hose 30, 30, at a point in each where they would otherwise be dangerously strained by their own weight and the weight of oil therein, and also to connect each jackstay 35 with a jackstay pennant 36. It is important, moreover, to maintain the oil hose 30, 30, as free as possible from bends which tend seriously to cut down the rate of oil flow therefrom.

Referring to Figs. 5, 6 and 7, I have provided a saddle 42 having a curved portion 45 for supporting the hose free from sharp bends. The saddle 42 is hung from supporting hawser 2, for example, by means of the hook 50, attached to the uprights 40, 41. I 110 preferably attach the end of the last jackstay section 32 to upright 41 by means of link 43. It will be apparent that in order to prevent undue longitudinal stress on each hose 30, 30, as well as excessive sagging between the points of support for the hose, the jackstay 35 must be held taut. To accomplish this I connect the opposite upright 40^a 120 with the jackpennant 36, which leads over pulley 37 and is attached to winch 390, each 125

jackpennant 36 being conveniently wound upon gypsy heads 391 and 392, respectively, so that by rotation of the latter, any desired tension may be placed in the jackstay. By appropriate clutch mechanism, a winch 390 may be used to operate both the jackpennant 36, and the block 20, by means of the lines 25. When the winch 390 provides the requisite tension in the jackstays 35, a clamp 47, engages the supporting hawser 2 for example, operated by toggle links 49 and 72 attached to the plates 70 by means of pin 71. The clamp 47 may conveniently have an arcuate bearing surface 48. By this means I am able to keep the jackstay 35 under the desired tension and yet allow for slipping in case an excessive strain in the jackstay 35 should be set up. The jackpennant 36 is attached to the upright 40 by means of a swivel connection 44 to avoid twisting stresses in the jackpennant 36. In case the clamp slips a winchman may take a manila line attached to the jackstay 35 and pull upon it with the aid of the winch 390 or capstan (not shown) until the jackstay is again under the desired tension.

The haul-down blocks 20, 20 are paid out to permit the hose to be clear of the water when all connections are made, and the pumping operations may then begin. After the fueling operations are finished, the oil is blown from the hose, the latter is detached from the ship receiving the fuel; the main cable is hauled down by means of winch 390 to a position conveniently close to the deck and the hose manually hauled back to the fuel ship. During the fueling operation, the ships may proceed underway at a speed of even twelve knots. When fueling is completed the ships may be slowed down. When the hose has been hauled in, the supporting hawsers 2 and 3 are wound in by means of the automatic machines 10.

As an alternative to the arrangement above described for maintaining tension in the jackstay 35, I may provide the arrangement shown in Fig. 4, in which the jackstay pennant 36' is connected to an automatic tension engine 10^a similar to automatic tension engine 10' operating the hawser 2'. By this arrangement I rely upon the automatic tension engine 10^a to maintain a desired tension in the jackstay 35', instead of the winch 390 and the clamp 47. This arrangement has the advantage that the constant tension is at all times maintained in jackstay 35 and I may, therefore, dispense with clamp 47; Figs. 11, 12 and 13 showing the support 42' without the clamp. In this modification I provide a haul-down block 20' connected by tackle 21' to the deck through block 22' attached thereto. The block 20' and tackle 21' are operated by winch 23'. The dotted lines indicate the position of the lines preparatory to attaching and detaching the hose.

I will now describe in detail certain parts of the apparatus which are necessary or advantageous for the carrying out of my invention.

The hangers 31 are exemplified in Figure 70 10 in which 33 denotes an endless manila strap adapted to grip the hose 30, and jackstay 35. The strap 33 is secured to the end portion 50 of the hook 52 by being looped around the shank portion 51, both ends passing through the eye 53. In order to securely lock the hook to the hawser 2, the hook is provided with a tongue 54 pivotally secured to the head of the hook by means of pin 56 and cotter 57. The end of the tongue 60 passes through a slot 61 and is held firmly against the edge 62 of the opposite face of the hook by means of spring 63, the latter being secured to the head of the hook by means of bolt 64. It will be seen that owing to the position of the pivot 56 with reference to the end portion 60 of the tongue, the resultant of any force exerted on the portion 61 by a movement of the hawser will pass substantially through the axis of the pivot 56, so that there will be no tendency for the end portion 60 of the tongue to move out of engagement with the contacting surface 62 against which it is firmly pressed by spring 63.

It will be noted that by means of mast 38 on the fuel ship, I am able to support the fuel hose 30 clear of the water, while providing an arrangement whereby the hose may be lowered when it is desirable to do so. By suspending the hose clear of the water, I achieve a notable advantage, in that the oil passing through the hose is not chilled by the cooler sea water, its viscosity increased and flow diminished. Furthermore, I thereby eliminate the drag caused by the sagging of the hose in the sea, which may amount to several thousand pounds additional stress in the towing hawsers.

It will be seen that I have provided a simple and effective means for supplying fuel to a ship while in motion, and while I have shown apparatus embodying my invention, it will be understood that the same is illustrative only and that the details thereof as well as the procedure may be varied considerably without departing from the spirit of my invention. What I claim and desire to secure by Letters Patent of the United States is:—

1. The combination with a fueling ship and a ship to be fueled, of a hawser elevated above the water connecting said ships, a hose, means for suspending said hose from said hawser, a distance line sagging into the sea and tending to maintain a uniform distance between said ships.

2. The combination with a fueling ship and a ship to be fueled, of a hawser connecting said ships, a hose, means for suspending said hose from said hawser, a cable secured at intervals to said hose and the ends thereof to

said ships and means to subject said cable to tension to prevent undue slipping of said hose longitudinally of the supporting hawser.

3. The combination with a fueling ship and a ship to be fueled, of a hawser elevated above the water connecting said ships, a hose supported on said hawser and means on the fueling ship for supporting said hawser sufficiently to clear the intervening water.
- 10 4. The combination with a fueling ship and a ship to be fueled, of a hawser connecting said ships, a hose supported by said hawser, means on the fueling ship for supporting said hawser at such a height that the hose will be 15 clear of the water, and means to bring a portion of said hawser between the support therefor and the ship to be fueled in proximity of the deck of the fueling ship to facilitate attaching the hose thereto.
- 20 5. The combination with a fueling ship and a ship to be fueled, of a hawser connecting said ships, a hose supported by said hawser, means on the fueling ship for supporting said hawser at such a height that the hose will be 25 clear of the water, a haul-down block on said hawser intermediate said supporting means and the edge of the ship and a tackle for said block for bringing a portion of said hawser into proximity of the working deck.
- 30 6. The combination with a fueling ship and a ship to be fueled, of a hawser connecting said ships, a hose suspended from said hawser by a plurality of hooks, slidably mounted on said hawser, a jackstay parallel with said hose and 35 secured thereto at a plurality of points and means for placing said jackstay under tension.

7. The combination with a fueling ship and a ship to be fueled, of a hawser connecting said ships, a hose, means for suspending said hose from said hawser, means for maintaining a uniform tension in said hawser, a cable connecting said ships and disposed parallel with said hawser and fastened to said 45 hose at a plurality of points, and means for maintaining uniform tension in said cable.

8. In an apparatus for supplying fuel to ships at sea, the combination of a hawser connecting a fueling ship with the ship to be fueled, a hose suspended from said hawser, a cable connecting said ships and secured at intervals to said hose, a support for the bend in said hose adjacent the first point of its suspension from the hawser, means on said 55 support for securing said cable and means on said support for frictionally securing said support to said hawser.

9. The apparatus as recited in claim 8 together with means for maintaining said cable and said hawser under uniform tension.

10. In an apparatus for supplying fuel to

ships at sea, the combination of a hawser connecting a fueling ship with the ship to be fueled, a plurality of hooks slidably engaging said hawser, means carried by said hooks for preventing disengagement thereof from the hawser, straps secured to the shanks of said hooks and a hose carried by said straps.

11. In a ship fueling apparatus, the combination with the fuel ship and the ship to be fueled, of a hawser extending between said ships, a hose also extending between said ships, means for supporting the hose from said hawser, means connected with the hose at intervals, means for putting said hose under a predetermined tension and automatically maintaining such tension.

12. In a fueling apparatus, the combination with a fuel ship and a ship to be fueled, of a distance hawser fixed to said ships, a supporting hawser fixed to the ship to be fueled and attached to the fuel ship through automatic tension means, means for maintaining uniform tension in said hawser and permitting the length of said hawser to vary as the distance between said ships varies, a fueling hose supported by said hawser and means for maintaining a predetermined tension in said hose.

13. The method of passing a liquid from one ship to another at sea by a device comprising a suspended cable and a hose, which consists in supporting the hose by the cable between said ships, placing a predetermined substantially constant tension on said hose and said suspended cable, and passing the liquid from one ship to the other through said hose.

14. The method of supporting a flexible conduit which consists in applying a predetermined tensioning force at a plurality of points along the conduit and applying a transverse supporting force at a plurality of points along the conduit.

15. The method of supplying oil from a fueling ship to a ship to be fueled which consists in suspending a hose between said ships at a plurality of points throughout the length thereof, applying tension at a plurality of points on the hose in a direction substantially longitudinal of it to oppose sagging therein and passing oil through the hose.

16. The method of supplying oil from a fueling ship to a ship to be fueled which consists in suspending a hose between said ships at a plurality of points throughout the length thereof, applying tension at said points on the hose in a direction substantially longitudinal of it to oppose sagging therein and passing oil through the hose.
